BORING APPARATUS

Henri Léon Georges Ricouard, Enghien-les-Bains, France

Application November 17, 1953, Serial No. 392,708

6 Claims. (Cl. 255—1)

The invention relates to apparatuses which break up the ground and remove the broken up material and which are capable of operating under dry or wet conditions. Boring apparatuses of this type comprise an elongated substantially cylindrical body which is suspended at the end of a cable and contains, slidably therein a movable block which forms a piston and which actuates grab scoops pivoted to the lower end of the cylindrical body. The scoops, when in their open position, constitute the boring tool and operate on the soil by percussion owing to the weight of the body and the movable block. When the movable block is raised by a controlling cable the scoops are caused to close and gather or seize the broken up soil.

These boring apparatuses possess various disadvantages. Generally two cables are necessary, one cable being employed for raising the boring apparatus and the other controlling the closing and opening of the scoops.

When the boring apparatus enters into contact with the soil during the boring operation, and above all when the bottom of the pit has a rounded shape, these scoops have a tendency to close. Furthermore, the reactions from the impact of the scoops on the soil are transmitted to the whole of the boring apparatus.

The invention has for an object to provide an improvement in this type of boring apparatus whereby the grab scoops are positively locked or held in their open position and are isolated from the rest of the mechanism and which enables these boring apparatuses to be used with a single cable which ensures both the hoisting of the boring apparatus and the control of the opening and closing of the scoops.

To this end, a rod connected to a controlling cable is slidably mounted in the movable block and constitutes at its lower end a wedge member which, when the scoops are in their open position, bears against and wedges the adjacent and cooperating portions of said scoops.

According to another feature of the invention, an abutment device causes the slidable rod to abut against the movable block when the latter rises to ensure the closing of the scoops.

When the boring apparatus has only one cable and is provided with a head which cooperates with a hooking ring, this cable includes an abutment member so arranged as to engage a retractable abutment, associated with the head, when the slidable rod is in its lower position and locks the scoops in their open position.

It can be seen that, owing to these various arrangements, these scoops may be positively locked or held in their open position by the wedge formed by the slidably rod and the portion of the cable situated inside the boring apparatus is thus put out of action since it is located between two fixed points which are constituted by the point at which the rod is wedged against the scoops and the abutments carried by the head of the boring apparatus. By merely hauling on the cable when the boring apparatus rests upon the soil, the slidable rod

2

and the movable block are raised resulting in the closure of the scoops, and the boring apparatus is hoisted.

According to another feature of the invention, utilized when the open grab scoops are required to effect several up and down percussion movements in the manner of a boring tool, the head of the boring apparatus is provided with a locking device which permits the retractable abutments to be locked in position so that they prevent the cable from operating the members controlling the scoops.

Other features and advantages of the invention will appear from the ensuing description with reference to the accompanying drawings given solely by way of example and in which:

Fig. 1 is a vertical sectional view of the boring apparatus showing the scoops of the grab in their open position,

Fig. 2 is a view similar to that of Fig. 1 but showing the grab closed,

Fig. 3 is a view partially in section of one detail of the apparatus,

Fig. 4 is an elevational view of one of the grab scoops,

Fig. 5 is a sectional view on line 5—5 of Fig. 4,

Fig. 6 is a vertical sectional view of the hooking ring,

Figs. 7, 8 and 9 are views showing different positions of the head of the boring apparatus and the hooking ring,

Fig. 10 is an elevational view partially in section of the locking device of the head of the boring apparatus,

Fig. 11 is a sectional view on line 11—11 of Fig. 10,

Fig. 12 is a fragmentary sectional view on line 12—12 of Fig. 11, and

Fig. 13 is a partial perspective view of the block controlling the scoops.

In referring to the drawings, it can be seen that the boring apparatus comprises three parts, a substantially cylindrical body 1, an upper cylindro-conical part 2 which is connected by arched portions 3 to a hooking head 4, and a lower ring 5 on which are pivotally mounted by pins or spindles 6 grab scoops 7. These three parts are interconnected by any means, not shown in the drawing, for example by nuts or locking collars in the manner well known in the art.

The ring 5 has a slightly downwardly flared shape and the scoops 7, two of which are provided in the illustrative embodiment, comprise adjacent their pivotal mounting on pins 6 flat bearing surfaces 8 which are adapted to abut against corresponding surfaces 9 provided on the ring 5 (see Figs. 4 and 5) so as positively to limit the opening movement of the scoops 7 and thus prevent the latter from assuming an excessive inclination away from the axis of the boring apparatus. At their lower ends, these scoops 7 are chamfered at 10 so that when the scoops penetrate the soil, their lower ends tend to move outwardly and thus urge the bearing surfaces 8 against the corresponding surfaces 9 provided on the ring 5.

Inside the body 1 is disposed, as known per se, a movable block 11 which forms a piston whose downward movement is limited by an annular abutment or shoulder 12 provided on the inner wall of the body 1. This block 11 is connected by ribs 13 (see Fig. 3) to a lower cylindrical sleeve or tube 14 which when assembled in the body 1 extends beyond the lower end of the latter. The block 11, ribs 13 and the sleeve 14 are advantageously cast in one piece as shown in Fig. 13. This sleeve 14 is connected by a key or pin 15 to a forked member comprising a tubular block 16 provided at its lower end with a fork 17. This fork 17 carries adjacent its lower end pins 18 which extend through elongated apertures 19 provided in side members 20 which are integral with the scoops 7.

The block or piston 11 is provided at its upper part with a cross-piece 21 against which bears a compression spring 22 which bears at its other end against a sec-

ond cross-piece 23 which is integral with the upper part 2 of the boring apparatus. Tubular members 24 and 25 serve to guide the spring 22 at its ends. The block 11 is connected to the sleeve 14 by a perforated conical member 26 and is provided at its lower part with apertures 27 and at its upper part with notches or crenels which form therebetween scraper members 28 for the inside wall of the body 1. The side wall of the block 11 is slightly spaced away from the wall of the body 1 so as to provide an annular space 29 between the walls, and at its lower part lower scraper members 30 are arranged between the apertures 27, these scraper members being located in the same vertical plane as the upper scraper members 28.

The grab is suspended from the positioning and hoisting member or jib by a chain or the like 31 which is prolonged by a cable or the like 32. The latter is associated with a device whereby a mechanical advantage is obtained. The illustrated device comprises a pulley block arrangement including a set of lower pulleys 33 and a set of upper pulleys 34. At the top of the pulley block 33, 34 the cable 32 is attached to an eye 35 adjustably connected to the head 4 by a nut 36.

The upper set of pulleys 34 is carried by a spindle 37 housed and maintained in position by a split pin 38 in a transverse tubular member comprising two sleeves 39 which are integral with the upper part 2 of the boring apparatus and are further supported by webs 40.

The lower set of pulleys 33 is carried by a spindle 41 which is supported by a hollow block or case 42 which is housed inside the block 11 and is urged downwardly by a spring 43. The latter is weaker than the spring 22 and at its upper end bears against the inner wall 44 of the end of the guide tube 24, which is integral with the cross-piece 21 and the block 11.

At the lower part of the case 42 is fixed by a nut 45 a cylindrical locking rod 46 which extends along the axis of the boring apparatus and slides in the sleeve 14 and the block 16 when the case 42 is displaced in the block 11. The rod 46 is provided at its lower end with a conical head which constitutes a wedge 47. The latter bears against and wedges the oblique bearing surfaces 48 of the side members 20 and thus ensures the positive blocking or locking of the scoops 7 in their open position. An elongated slot 49 is provided in the locking rod 46 for the passage of the key 15 and its position and length are such that when the grab assembly at the lower part of the boring apparatus is in the open position shown in Fig. 1, the upper end of the slot is a certain distance from the top face of the key 15. The clearance 50 thereby obtained is intended to ensure that the wedge 47 is allowed at least sufficient travel for wedging between the bearing surfaces 48 of the scoops under the action of the spring 43. Furthermore, any wear that might occur on the contacting bearing surfaces is in this way accommodated.

The upper part 2 of the body of the boring apparatus is closed by a perforated conical member 51 which carries an axially disposed ring 52 for guiding the cable 32. The locking head 4 is supported by a plate 53 which is integral with the arched members 3 and it comprises two radially disposed side members 54 which carry a tubular sleeve 55 in which is slidable a tube or slide 56 which at its lower part extends through the head 4 and the plate 53 and is urged downwardly by a spring 57 which bears against the head 4 and against a nut 58 screwed on the tube 56.

In the wall of the tube or slide 56 are provided two diametrically opposed apertures 59 which cooperate with pawls 60. The latter are pivotally mounted on pins 61 integral with the side members 54 and are so shaped that their weight causes them to rock in the direction of arrow *f* and bear by their outer heels against the upper face of the locking head 4.

An elongated slot 62 is provided in the wall of the slide 56 for cooperating with an abutment member 63 shown in the form of a screw which is carried by the sleeve

55 and is adapted to prevent rotation of the slide 56. The latter comprises, furthermore, an annular bearing surface or shoulder 64 which is adapted to bear against the upper face of the sleeve 55. At the upper part of the slide 56 there is provided an upwardly flared and rounded mouth 65 around which is provided an annular lip 66.

This slide 56 may be locked in position relative to the head 4 by means of a locking device shown in greater detail in Figs. 10 to 12. This device comprises a cylindrical block 67 rotatively mounted in a tubular housing 68 provided on the sleeve 55. At the inner end of the block 67 are provided two parallel axially extending flats which form therebetween a diametrically disposed, flat and substantially rectangular latch or locking member 69 which is adapted freely to enter a circular aperture 70 provided in the wall of the slide 56. Above this aperture 70 is provided an aperture in the shape of a vertical slot 71 whose width is slightly more than the width of the latch member 69. When the latter is in the horizontal position (Figs. 1, 10 and 11), the slide 56 is connected to the sleeve 55, and when the latch is in a vertical position (Figs. 2, 7, 8 and 9) the latch member is able to enter the slot 71 and the slide 56 is free to move longitudinally relative to the sleeve 55.

The block 67 is rotated by means of a key introduced in a square hole 72 provided in the outer end of the block and it is maintained in position in the housing 68 in the axial direction by a screw 73 which is screwed in this housing 68 and whose point engages an annular groove 74 in the cylindrical wall of the block 67. For the purpose of securing the latch 69 in either its locking operative position or its inoperative position, the block 67 is provided on its cylindrical wall with two concave notches 75 and 76 (Fig. 10) which are disposed at 90° from each other relative to the axis of the block 67 so that each one corresponds to one of the positions of the latch 69. A ball 77, housed in a small tube 78 which is integral with the housing 68 and whose axis is disposed perpendicular to that of the block 67, is adapted to engage either of these notches. The ball 77 is urged towards the block 67 by a spring 79 which bears against a screw-threaded plug 80 screwed in the tube 78.

The head 4 is adapted to cooperate, through the medium of the pawls 60, with a special chain link 81 comprising a plate 82 which is carried by the chain 31 adjacent the connection of the latter to the cable 32. The head 4 is adapted furthermore to cooperate, through the medium of the slide 56 and the horizontal bearing surfaces 83 (see Figs. 6-9) provided on the side members 54, with hooking means. The latter is suspended from the positioning and hoisting means for the boring apparatus, which is not shown in the drawing. The chain 31 and the cable 32 pass through the hooking means.

The hooking means, which are of known type, are shown in Figs. 6 to 9. They comprise a support member 84 which is suspended by two cables or chains 85 from, or otherwise connected to the hoisting apparatus and supports a cylindrical block 86 which the slide 56 is adapted to enter and abut against an upper annular bearing surface. In the cylindrical wall of the block 86 are provided two diametrically opposed apertures 87 in which two pawls 88 are adapted to engage. These pawls are pivotally mounted on pins 89 carried by outer webs 90 integral with the block 86. The pawls 88 are so adapted and arranged that under the action of their own weight, they tend to rock in the direction of arrows *f*. A part of one pawl 88 has been broken away in Figs. 6 to 9 for the sake of clarity.

The unit comprising the block 86 and the webs 90 is surrounded by a ring 91 which is movable in the vertical direction and is provided with apertures 92. The outer ends of the pawls 88, relative to the axis of the block 86, extend through these apertures 92. The travel of the ring 91 relative to the block 86 is limited by a finger or stop member 93. The latter is secured to the ring 91 and extends through a vertical slot 94 provided in a plate 95

which is integral with the webs 90. The base of the ring 91 may enter into contact with the bearing surfaces 83 of the head 4.

The boring apparatus operates in the following manner:

In Fig. 1 the boring apparatus has been shown in its position for continuously operating as a boring tool, the scoops being in their open position. The slide 56 is locked in its upper position by the latch 69 which is in its horizontal position, the spring 57 is compressed and the link 81 is held down by the pawls 60. While the boring apparatus is actually suspended from the chain 31, the plate 82 urges the pawls 60 against the head 4. Hence the apparatus is suspended from the chain 31 solely by means of the link plate 82 and the pawls 60. Therefore no pull is exerted on the cable 32 associated with the pulley block 33, 34. The spring 22 is predominant and urges the block 11 downwardly against the abutment 12 and the spring 43 holds the wedge 47 of the locking rod 46 between the bearing surface 48 of the scoops 7. The latter are therefore held in the required open position and are prevented from further outward movement by the support of the bearing surfaces 8 and 9 and from movement towards the axis of the grab by the wedge 47 which thus prevents the scoops from closing. Owing to this double and positive support of the scoops and to the fact that the cable 32 is isolated by the link plate 82 from any strain due to hoisting the boring apparatus, the mechanism of the latter is shielded from the movements of the apparatus and from the impact of the grab scoops on the soil.

If it is desired to end the boring operation and remove the broken up soil by closing the grab, before allowing the boring apparatus to descend once more, the block 67 is rotated through 90° so as to bring it in the inoperative position for releasing the slide 56, the latch 69 being then vertical and opposite the slot 71. At the moment when the grab rests on the bottom of the excavated pit, slack is given to the chain 31, the link 81 drops through the head 4 and frees the pawl 60. The spring 57 urges the slide 56 downwards, the latch 69 enters the slot 71 and, in descending, this slide 56 bears against the ends of the pawls 60 and causes them to pivot in the direction opposite to that of arrow *f* and retract their ends from the inside of the slide 56 and thus permit the free upward travel of the link plate 82.

The chain 31 is then wound up and, since the link plate 82 is free to rise and pass through the slide 56, this movement of the chain is transmitted to the cable 32 and thence, through the pulley block 33, 34, to the case 42 which rises, displaces the locking rod 46 and compresses the spring 43. The wedge 47 rises and the scoops 7 are unlocked. If the cable is continued to be drawn up, the lower edge of the aperture 49 subsequently enters into contact with the key 15 and causes the block 16, the sleeve 14 and the block 11 to be raised and the scoops 7 thereupon close and the spring 22 is in turn compressed (see Fig. 2). The boring apparatus is then raised up to its hooked position in the hooking means.

When the head 4 is in the neighborhood of the hooking means the slide 56 enters the block 86 and the bearing surfaces 83 enter into contact with the ring 91 which they raise. The freed pawls 88 then rock in the direction of arrow *f* and return to the hooking position as shown in Fig. 7. If slack is given to the cable 32 the boring apparatus descends a short distance and the annular lip 66 bears against the pawls 88 and thus ensures the hooking of the boring apparatus to the hooking means (see Fig. 8). The ring 91 moves downwardly onto the pawls 88 and the weight of the boring apparatus is supported by the slide 56, the spring 57 and the nut 58. The spring 57 is compressed and the slide 56 rises relative to the sleeve 55. If further slack is given to the cable 32 the latter passes through the pulley block 33, 34, the action of the spring 22 becomes once more predominant and the block 11 once more descends and causes, through the

medium of the sleeve 14 and the block 16, the scoops 7 to open and empty the contents of the grab.

For unhooking the boring apparatus and lowering the latter with the grab open, more slack is given to the cable 32 until the link plate 82 is situated once more below the pawls 60. The boring apparatus is then in the position shown in Fig. 1; the scoops are locked in their open position and the springs 22 and 43 are expanded. The cable 32 is then slightly drawn up, the plate 82 of the link 81 bears against the pawls 60, the slide 56 rises with the boring apparatus and, as soon as the lip 66 leaves the pawls 88, the latter rock in the direction opposite to that of arrow *f* under the action of the weight of the ring 91 and are retracted from the inner wall of the block 86. The cable 32 is released and the boring apparatus, which is freed from the block 86 (see Fig. 9), is able to descend with the scoops in their open position as shown in Fig. 1. Before the boring apparatus is allowed to descend, the slide 56 may be once more locked to the sleeve 55 by rotating the latch 67 or, if it is desired that the boring apparatus continue to remove the broken up soil, the latch 67 is left in its inoperative position as shown in Fig. 9.

When the boring operation or excavating operation is carried out under water, the latter freely circulates through the body of the boring apparatus and through the block 11. The perforated members 26 and 51 prevent any entry of stones or other foreign bodies and the baffle-like action of the apertures 27, the scrapers 28 and 30 and the annular chamber 29 results in a turbulent circulation which washes out any solid bodies that might pass through the perforated members 26 and 51 and thus considerably lessens the risk of seizure of the various moving parts and especially ensures that the block 11 does not become blocked in the cylinder 1.

It is clear that, owing to the upper and lower locking devices, a single cable or chain may be used for both hoisting the boring apparatus and controlling the opening and closing movements of the grab scoops. The portion of the cable which controls the scoop actuating members is completely isolated from the portion forming the hoisting cable or chain, when the boring apparatus operates as a boring tool, i. e., when the scoops are locked in their open position.

Although a specific embodiment of the invention has been described hereinbefore, it is to be understood that many changes and modifications may be made therein without departing from the spirit of the invention or the scope of the appended claims.

In the illustrative embodiment it has been mentioned that the device whereby a mechanical advantage is obtained is in the form of a pulley block. It is obvious that any other device which gives the same result may be used.

Having now described my invention what I claim as new and desire to secure by Letters Patent is:

1. Boring apparatus suitable as a boring tool for breaking up the ground and as a grab for removing the broken up material, which comprises flexible control means, a substantially cylindrical body connected to said control means, a movable block slidable axially in said cylindrical body, the movements of said block being controlled by said control means to which it is operatively connected, scoops pivoted to the lower part of said cylindrical body, a tube integral with said movable block and downwardly extending, extensions on said scoops, these extensions being connected to the lower part of said tube by means of pin and elongated slot arrangements so that movement of said block in one direction causes said scoops to open and movement of said block in the other direction causes said scoops to close, oblique bearing surfaces provided on said extensions, a rod which is slideable in said tube, connected to said control means at its upper end and provided at its lower end with a wedge which engages said oblique bearing surfaces when the

scoops are open, an elongated slot provided in the locking rod, a pin carried by said tube and extending through said slot, a spring of which one end bears against the upper part of the movable block and the other end urges the locking rod downwards, and a second spring stronger than the first spring interposed between the upper part of the cylindrical body and the movable block for urging the latter downwards.

2. Boring apparatus as claimed in claim 1, further comprising abutments carried by the lower part of the cylindrical body for limiting the outward opening movements of the scoops.

3. In a boring apparatus used both as a boring tool for breaking up the ground and as a grab for removing the broken up material, the combination: a substantially cylindrical body having a vertical axis, a movable block slideable axially in said cylindrical body between an uppermost and a lowermost position, scoops pivoted to the lower part of said cylindrical body, a pin and elongated slot arrangement connecting said block with each of said scoops whereby downward movement of said block to said lowermost position causes the scoops to open and assume their boring positions and upward movement of said block to said uppermost position causes the scoops to close inwardly towards the axis of said cylindrical body and thereby assume their material-holding position, a locking rod slideable in said block in a direction parallel with said axis between an extreme upper position and an extreme lower position, bearing surfaces provided on the scoops, a wedge formed on the lower end of said locking rod and adapted for insertion between said bearing surfaces when the scoops are in their open position and said locking rod is in said extreme lower position, means for ensuring that the block and the locking rod have a tendency to move downwardly relative to said body, controlling means for controlling the position of the locking rod relative to said body, these controlling means comprising a flexible member one end of which is operatively connected to the locking rod through the medium of a device whereby a mechanical advantage is obtained, the other end of said flexible member being adapted to be operatively connected to the device adapted to hoist and control the boring apparatus, whereby when the flexible member is pulled relative to said body the locking rod is caused to rise to said extreme upper position thereof and disengage from said bearing surfaces and thereafter raise the block to said uppermost position thereof and when the flexible member is released relative to said body the locking rod descends relative to said body, the block descending with this locking rod until the block attains said lowermost position whereupon the locking rod in continuing its downward movement moves to said extreme lower position and the wedge inserts itself between said bearing surfaces.

4. Boring apparatus suitable as a boring tool for breaking up the ground and as a grab for removing the broken up material, which comprises a single flexible hoisting and control means, hooking means supported above the ground, a substantially cylindrical body suspended from said hoisting means and movable by the latter between the ground and said hooking means, a block movable axially in said body, the movements of said block being controlled by said hoisting means to which it is operatively connected, scoops pivoted to the lower part of said body, bearing surfaces provided on said scoops, a device for operatively connecting said block to the scoops whereby downward movement of said block relative to said body causes the scoops to open and upward movement of said block causes the scoops to close, a locking rod in the form of a wedge, slidably mounted in the said block, controlled

by said hoisting means to which it is connected and adapted and arranged for engaging said bearing surfaces and thereby locking the scoops when they are in their open position, the connection between said cable and said block and said locking rod being so adapted and arranged that said locking rod is disengaged from said bearing surfaces before said block is moved in the direction to close the scoops, retractable abutment means mounted at the upper part of said body and movable between an operative position and a retracted inoperative position, an abutment member fixed on said hoisting means in such position that it is co-operable with the retractable abutment means and is capable of moving between an upper position above and a lower position below the retractable abutment means and is below the latter when the locking rod is in its position for locking the scoops, this retractable abutment means being biased to its operative position in which it is adapted to allow the abutment member to move to its lower position but prevents it from moving up to its upper position, a slide cooperating with the retractable abutment means and mounted at the upper part of said body and movable longitudinally of the latter between an upper position in which it allows the retractable abutment means to assume either of its two positions and a lower position in which it holds the retractable abutment means in its retracted position, elastically yieldable means associated with the slide to urge the latter to its lower position and cause retraction of the retractable abutment means, projecting means provided on the slide, said hooking means being so constructed and arranged as to hook on said projecting means when said body is raised up to the hooking means by said hoisting means, whereby said body can be suspended from the hooking means through the medium of the slide, said elastically yieldable means being such as to yield elastically under the weight of the suspended part of the apparatus so that by suspending said body through the medium of the slide the latter moves to said upper position thereof.

40 5. Boring apparatus as claimed in claim 4, wherein said retractable abutment means comprises pawls which are mounted for pivotal movement about axes transverse to the longitudinal axis of said body and are capable of engaging and preventing upward movement of said abutment member but allowing downward movement of the latter, said slide is a tube which encompasses said hoisting means and which when moved to its lower position relative to said body urges said pawls downwardly about their axes to their retracted inoperative position.

45 6. Boring apparatus as claimed in claim 5, wherein locking means are mounted at the upper part of said body for engaging said tube and locking it in its upper position when it is desired to retain said abutment member in engagement under the pawls, whereby said body can be raised off and dropped onto the ground a plurality of times without causing closure of the scoops.
